Tingkang Xia, Esq.

(57) **CLAIM**

The ornamental design for a keyboard dock, as shown and
described.

DESCRIPTION

FIG. 1 is a top, front and left side perspective view of a
keyboard dock showing my new design;

FIG. 2 is a top, front and right side perspective view thereof;

FIG. 3 is a top, rear and left side perspective view thereof;

FIG. 4 is a top, rear and right side perspective view thereof;

FIG. 5 is a bottom, front and left side perspective view
thereof;

FIG. 6 is a bottom, rear and right side perspective view
thereof;

FIG. 7 is a front view thereof;

FIG. 8 is a rear view thereof;

FIG. 9 is a left side view thereof;

FIG. 10 is a right side view thereof;

FIG. 11 is a top view thereof;

FIG. 12 is a bottom view thereof;

FIG. 13 is an enlarged view of portion A in FIG. 1;

FIG. 14 is an enlarged view of portion B in FIG. 1;

FIG. 15 is an enlarged view of portion C in FIG. 2;

FIG. 16 is an enlarged view of portion D in FIG. 2;

FIG. 17 is an enlarged view of portion E in FIG. 3;

FIG. 18 is an enlarged view of portion F in FIG. 3;

FIG. 19 is an enlarged view of portion G in FIG. 4;

FIG. 20 is an enlarged view of portion H in FIG. 4;

FIG. 21 is an enlarged view of portion I in FIG. 11; and,

FIG. 22 is an enlarged view of portion J in FIG. 11.

The evenly dashed broken lines illustrate environmental
structure and form no part of the claimed design.

The unevenly dashed broken lines, which denote the limits
of the claim, represent a boundary that forms no part of the
claimed design.
